INTEGRAL FLASH BOX CAMERA

Arthur H. Crapsey, Jr., Rochester, N. Y., assignor to Eastman Kodak Company, Rochester, N. Y., a corporation of New Jersey

Application October 12, 1956, Serial No. 43,343

Term of patent 14 years

(Cl. D61—1)

Fig. 1

Fig. 2

Fig. 1 is a perspective view of an integral flash box camera taken from the front and showing my new design; and

Fig. 2 is a perspective view taken from the rear of the integral flash box camera shown in Fig. 1.

I claim:

The ornamental design for an integral flash box camera, as shown.
